UNITED STATES PATENT OFFICE.

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS.

WARMING OVEN.

Application filed April 16, 1925. Serial No. 23,481.

To all whom it may concern:

Be it known that I, STANLEY H. HOBSON, a citizen of the United States, residing at Rockford, in the county of Winnebago and State of Illinois, have invented certain new and useful Improvements in Warming Ovens, of which the following is a specification.

This invention relates to stove construction and more particularly to a novel warming oven and construction of a flexible sectional closure or door therefor.

Doors for warming ovens of various types of stoves are usually curved and swing on a pivot in an inwardly and downwardly extending arc. This causes the door to intercept the warming oven space and preclude convenient access thereto for permitting the placing and removal of the articles of food, especially in the back portion of the oven which is cut off by the door when swung to a supposedly open position. Furthermore, closures or doors of warming ovens have been unsightly, heavy and cumbersome in comparison with the service rendered, owing to the employment of heavy cast metal parts much out of proportion to their utility.

The present device overcomes the above objections and provides a novel closure for warming ovens which is extremely attractive in appearance and may be made to conform to the enameled or other parts of the stove, as well as being constructed of light sheet metal, easy to manipulate and which will move without noise and remain in any desired adjusted position without in any manner obstructing the warming oven space or preventing free access to the same for placing or removing food stuff.

The invention also comprehends a novel door or closure embodying a plurality of sections with means for maintaining the sections in contact, together with guide means therefor which permit the closure or sections to be moved without undue friction and without a squeaking noise usually caused by the movable contact of metal with metal, as well as to prevent the door binding.

My invention further provides for adjustment of the door with reference to the front opening and walls of the warming oven so as to cause the parts to properly fit and work with ease.

Other objects and attendant advantages will be appreciated by those skilled in this art

as the invention becomes better understood by reference to the following description when considered in connection with the accompanying drawings in which—

Figure 1 is a fragmentary front elevation partly broken away and a section showing an elevated oven and a warming oven closure therefor constructed in accordance with the invention.

Fig. 2 is a vertical sectional view taken on the line 2—2 of Fig. 1, and

Fig. 3 is a fragmentary sectional view taken on the line 3—3 of Fig. 2.

Referring to the drawings in detail wherein I have illustrated an embodiment of the invention and in which similar reference characters designate corresponding parts throughout, 4 designates the back splasher wall of a stove or range, preferably a gas stove, having an elevated oven 5 with the usual frame 5', sides and back, and the door 6. A cast metal frame 7 is provided above the oven 5 and includes spaced side members having curved front portions as shown. The warming oven has sides 8 provided with flanges 9 bolted to the top flanges 10 of the sides of the bake oven 5 as indicated at 11. This structure includes a plate 12 which forms the top of the bake oven and the bottom of the warming oven which is bolted to bottom flanges 13 extending inwardly from the sides 8, as indicated at 14. The plate 12 has a surrounding depending flange 15 substantially corresponding to the depth of the frame 5' and closing the space between the top and bottom walls thereof as seen in Fig. 2. The side portions of the frame 7 are of right angular cross-section as distinguished from the channel cross-section at the front corresponding to the top of the frame 5' of the oven 5, as shown in Fig. 3. A back plate 16 is secured to the sides 8, flange 15 and depending flange 17 of a top wall 18 having flanges 18' abutting sides 7 and bolted at 19' to flanges 8' of sides 8.

Angular lugs 19 are cast integral with the sides of the frame 7 and are bolted to the bottom 12 of the warming oven as indicated at 20. These lugs have inwardly and upwardly offset apertured ears 21 extending horizontally to pivotally receive the upturned ends 22 of the inwardly extending or crank portions 23 of guide rods 24 positioned at each side of the warming oven. These rods have curved portions lo-

cated under the top flanges of the curved portions of the sides 8 and straight portions extending downwardly at a slight incline beneath the top 18.

5 An angle bar 25 is bolted to the back 16, being preferably provided with longitudinal slots 26 above and below which ribs 27 are provided to receive the nuts 28 of bolts 29 by which the bar is secured through holes 10 in the back 16 and also to adapt the bar and rods 24, which are connected thereto as will be subsequently described, to be adjusted laterally and horizontally with respect to the sides of the frame 7 of the warming oven. The bar 25 has downwardly inclined ends 30 with forwardly offset apertured lugs 31 spaced from the back 16 through which the threaded ends of the rods 24 are passed and anchored by nuts 32 on either 20 side.

While I have described a particular mounting for the rear ends of the rods 24 or connection between the same and the back of the warming oven, it is to be understood that any other suitable connection may be provided. However, this construction permits convenient connection of the rods 24 at the back owing to the same being extremely accessible.

30 The closure proper is made up of a series of slats or sections 33, preferably of sheet metal which may be enameled or otherwise finished to conform to the remainder of the stove. These sections are in the form of 35 flat narrow strips with their ends disposed beneath the frame sides 7 and having their edges bent to form rearwardly extending converging flanges 34. These flanges are provided with apertures 35 to take the guide rods 24 whereby the sections may be slidably mounted thereon and in order to prevent a squeaking noise due to the movement of the sections by contact of the metal parts with each other, the edges of the material at the 45 openings 35 are rolled or formed with beads 36 to permit the sections to move without noise or undue friction as would occur if the raw edges were exposed.

The sections 33 are flexibly connected and 50 disposed with their angular portions in contact and are maintained in this position so as to form tight joints between the sections. For this purpose wires 37 are provided and extend through small openings 38 in the 55 flanges 34 between the rods 24 and holes 35. These wires are headed at their lower ends as indicated at 39 to engage the top flange of the lower section 33 and their opposite ends are bent to form open loops 40 to take 60 bent cross pins 41 between which and the adjacent flange of the top section 33 coiled expansion springs 42 are mounted on the wires or other flexible strands provided for this purpose, to exert pressure against the 65 sections and maintain the same in contact

under tension whereby to seal the joints between the sections. The bottom edge of the lower section is preferably turned back as indicated at 43 and said section is provided with a knob 44 to manipulate the closure whereby it may be opened and closed by sliding the same on the guide rods 24.

Owing to the flanges 34 of each section being bent back in converging relation, the adjacent flanges at the abutting edges of 75 the sections 33, are disposed in diverging relation as clearly indicated in Fig. 2 whereby to allow the necessary angular movements of the sections relatively to conform to the curvature of the guide rods and move 80 freely thereon at any required arc. It is also pointed out that the portions 23 permit the adjacent ends of the rods 24 to swing in an arc outwardly and inwardly to properly space the rods according to the distance between the holes 35 and permit the door to be opened and closed without undue friction. In fact, the door can be moved with ease either in raising or lowering the same and the friction between the parts is only such as to permit the door to remain in any desired position to which it is moved or adjusted. Owing to the upper rear portions of the guide rods 24 being slightly inclined downwardly and rearwardly, the door can be moved more freely and will be prevented from closing of its weight from a partly open position, although this is not likely to occur even if the parts are quite loose.

100 While I have described what I now consider to be the preferred embodiment of the invention, it is to be understood that the device is susceptible of wide changes and variations in the construction, arrangement and purposes of the parts as well as the materials used, without departing from the spirit and scope of the invention as will be hereinafter defined in the claims.

110 I claim:

1. In a warming oven, a closure having side members with curved portions adjacent an opening therein; of a closure including abutting sections flexibly connected and adapted to be moved to cover and uncover the opening, guides on which said sections are movably mounted, and resilient means to retain said sections in contact.

115 2. A warming oven having side frame members with curved portions and an opening for obtaining access to the oven space at said curved portions, guide rods having curved portions at said opening, flanged sections provided with openings in the flanges thereof through which the rods extend to movably mount the sections on the rods; and means to resiliently retain the sections in abutting relation.

120 3. The combination with a warming oven having a front opening and angular frame

members at the sides of the opening; of rods beneath said angular members and adjustably mounted at the back of the oven, said rods being adapted for lateral displacement, and a closure on said rods comprising flanged metal sections, the flanges of said sections having openings with rolled edges movably engaging the rods, and flexible connections between the flanges.

4. The combination with a stove having an oven provided with an opening for obtaining access thereto; of guide rods having curved portions movably anchored at the front of the bottom portion of the oven and substantially horizontal rearwardly extending portions anchored at the back of the oven, a plurality of closure sections having rearwardly converging edge flanges provided with openings receiving the rods for movably mounting the sections thereon, said sections abutting and the adjacent flanges of the sections being disposed in diverging relation, flexible members extending through and linking together all of the flanges, said members having means at their ends to prevent displacement of the sections therefrom, resilient means mounted on the flexible members to hold the sections in contact while permitting the same to conform to the curvature of the rods or move in a straight line when shifted to open and closed positions, and means for shifting the sections.

5. The combination with an enclosure having an opening; of guides adjacent the opening, a closure including abutting narrow sections extending across the opening and slidably mounted on the guides, flexible means connecting the sections, resilient means holding the sections in contact, and a handle on one of the sections.

6. The combination with metallic guide rods and flanged metal sections having openings in the flanges thereof slidably mounting the sections on the rods, said flanges being rolled at the edges of the openings.

7. The combination with a stove compartment having an opening through which to place articles in the compartment, of a linked, flexible closure for said opening to be moved from a position closing the opening to a position away from the opening within the compartment and to one side of the opening leading into the compartment, said closure comprising a plurality of sheet metal slats of a channel form arranged with the flanges of adjacent slats in abutting relation, said flanges being provided with registering openings, means inter-connecting said slats for movement together, a pair of

guide rods for the opposite ends of said slats received in the openings in the flanges thereof extending from the opening in said compartment to a point within the compartment, a support having the inner ends of said rods secured thereto, and individual fastenings for the outer ends of said rods.

8. The combination with a stove compartment having an opening through which to place articles in the compartment, of a linked, flexible closure for said opening to be moved from a position closing the opening to a position away from the opening within the compartment and to one side of the opening leading into the compartment, said closure comprising a plurality of sheet metal slats of a channel form arranged with the flanges of adjacent slats in abutting relation, said flanges being provided with registering openings, means inter-connecting said slats for movement together, a pair of guide rods for the opposite ends of said slats received in the openings in the flanges thereof extending from the opening in said compartment to a point within the compartment, a support having the inner ends of said rods secured thereto, and individual fastenings for the outer ends of said rods.

9. The combination with a stove compartment having an opening through which to place articles in the compartment, of a linked, flexible closure for said opening to be moved away from a position closing the opening to a position away from the opening within the compartment and to one side of the opening leading into the compartment, said closure comprising a plurality of sheet metal slats of a channel form arranged with the flanges of adjacent slats in abutting relation, said flanges being provided with registering openings, means inter-connecting said slats for movement together, a pair of guide rods for the opposite ends of said slats received in the openings in the flanges thereof extending from the opening in said compartment to a point within the compartment, a support having the inner ends of said rods secured thereto, and individual fastenings for the outer ends of said rods, said support being adjustable laterally with respect to said compartment for simultaneous adjustment of the inner ends of said rods.

STANLEY H. HOBSON.
